UNITED STATES PATENT OFFICE.

CHARLES JAMES JONES, OF MARSHALL, TEXAS.

RAILROAD-TIE.

1,383,954.

Specification of Letters Patent. Patented July 5, 1921.

Application filed April 1, 1921. Serial No. 457,715.

To all whom it may concern:

Be it known that I, CHARLES JAMES JONES, a citizen of the United States, residing at Marshall, in the county of Harrison and State of Texas, have invented a new and useful Railroad-Tie, of which the following is a specification.

This invention relates to railway ties and fasteners, and more particularly to a metallic tie and fastener designed to replace the wooden tie now in general use.

The primary object of the invention is to provide a tie of this character having a novel form of securing means for securing a rail thereto, the securing means being of a construction to prevent spreading of the rails supported thereby.

A further object of the invention is to provide a device of this character which may be readily and easily positioned, the tie being provided with means to eliminate lateral movement thereof or creeping, when a train is passing thereover.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 illustrates a side elevational view partly broken away, of a tie constructed in accordance with the present invention.

Fig. 2 illustrates a perspective view of a tie showing a rail as secured thereto.

Fig. 3 illustrates a perspective view of a tie and rail disclosing a modified form of securing means employed at the adjacent ends of rails.

Fig. 4 illustrates a perspective view of a tie showing a rail as secured, the view being taken from the opposite side of the rail.

Fig. 5 illustrates a sectional view through a tie and securing means, on line 5-5 of Fig. 1.

Fig. 6 illustrates a sectional view taken on line 6-6 of Fig. 1.

Referring to the drawings in detail, the tie which is formed of metal, includes opposed flanges 5 which extend vertically from the base 6, the base being provided with a

plurality of openings 7 to permit rain and moisture to pass therefrom.

Formed integral with the base 6 and extending transversely thereof, are a plurality of ribs 8, which ribs having tapering side 60 edges to permit the same to readily embed themselves in the road bed on which the tie is positioned.

Adjacent to the ends of the tie, and formed in the base 6 thereof are suitable 65 openings to accommodate the extensions 9' that are formed integral with the securing means, and which restrict movement of the securing means with respect to the tie.

The securing means includes a body 9 70 which is of a width equal to the distance between the flanges 5, so that the body may closely fit within the tie in a manner to prevent rattling of the securing means when a train is passing over the rails secured 75 thereby.

Extending laterally from the body 9 and formed integral therewith, are the lugs 10 which are fitted within suitable openings provided in the flanges 5, the openings being 80 of depths so that the upper edges of the lugs are in a plane flush with the upper edges of the flanges 5 to permit the rail to lie flush on the upper edges of the flanges.

A curved arm 11 is formed integral with 85 the body 9, the rail engaging surface of the arm being of a construction to conform to the curvature of a rail, so that the arm will closely fit the rail to prevent movement thereof, and as shown, the body 9 is provided with openings to accommodate the bolts 12, which coöperate with the arm 11 to secure a rail to the tie.

The bolts have upwardly extending extremities 13 which embrace a portion of a 95 rail base and force the rail into close engagement with the arm 11, when the nuts 14 operating on the threaded portions 15 of the bolts, are operated to move the extremities 13 into close engagement with the rail. 100

The extensions 9' of the blocks are each provided with an opening, the upper edge of which lies in a plane flush with the lower edge of the tie and accommodates a pin 16 which is driven into the opening and frictionally engages the lower wall of the base 6 of the rail. Thus it will be seen that the securing means is firmly connected with the tie.

In the form of the invention as illustrated 110

by Fig. 3 of the drawings, the securing means is substantially the same as that described, except that the arm 17 is of a width to span the space between adjacent rail sections, to brace the rail sections at their points of connection.

In order that the rails will be held against creeping, recesses 18 are formed in the base thereof, the recesses accommodating the hook members 13. These recesses it will be observed are of lengths to permit of contraction and expansion of the rails, but restrict such movement if the movement of the rails is beyond a predetermined point.

In view of the foregoing it will be readily seen that in the construction of a track, wherein ties of this character are employed, it is unnecessary to use a gage in order to aline the rails, since each tie is a gage within itself.

Having thus described the invention, what is claimed as new is:—

1. In a device of the character described, a metallic tie having openings formed adjacent to the ends thereof, fasteners comprising body portions associated with the tie, the body portions having extensions positioned within the openings, a curved arm forming a part of each fastening device, said curved arm adapted to embrace a portion of the rail, a bolt passing through each body portion and having a curved extremity embrac-

ing a portion of the rail, and means coöperating with the extensions for securing the extensions to the tie.

35

2. In a device of the character described, a metallic tie including opposed flanges, said tie having an opening formed adjacent to each end, fastening devices supported between the flanges and having extensions passing through the openings, each of said extensions having an opening, locking pins passing through the openings of the extensions for securing the fastening devices to the tie, and means forming a part of the fastening devices for embracing a portion of a rail for securing the same to the tie.

40

3. In a device of the character described, a metallic tie having opposed flanges, a fastener positioned between the flanges, means for securing the fastener between the flanges, an integral arm forming a part of the fastening member and embracing one portion of the rail, and removable means extending through the fastener and contacting with a rail for securing the rail against movement in one direction.

45

In testimony that I claim the foregoing as my own, I have hereto affixed my signature in the presence of two witnesses.

CHARLES JAMES JONES.
